UNITED STATES PATENT OFFICE.

WILLIAM E. PEIRCE, OF SAN FRANCISCO, CALIFORNIA.

TRANSMITTER OR REPRODUCER.

1,144,236.

Specification of Letters Patent. Patented June 22, 1915.

Application filed October 23, 1912. Serial No. 728,192.

To all whom it may concern:

Be it known that I, WILLIAM E. PEIRCE, a citizen of the United States, residing at San Francisco, in the county of San Francisco and State of California, have invented 5 certain new and useful Improvements in Transmitters or Reproducers; and I do hereby declare the following to be a full, clear, and exact description of the invention, such as will enable others skilled in the art to which it appertains to make and use the same.

This invention relates primarily to the telegraphic art, has especial reference to 15 transmitters or reproducers for transmitting or reproducing messages sent by the use of the Morse or other code, has for its object a very sensitive instrument which will readily engage the characters produced on 20 a strip of paper by a Morse key or other equivalent means and transmit or reproduce them.

The invention consists in certain improvements in construction, which will be fully 25 disclosed in the following specification and claims.

In the accompanying drawings, which form part of this specification:—Figure 1 represents a top plan view of an instrument embodying my invention. Fig. 2 is a side elevation, and Fig. 3 a vertical transverse section on line 3—3, Fig. 2.

Reference being had to the drawings and the designating characters thereon, the numeral 1 indicates a base-plate of usual construction provided with binding-posts 2, 3. The instrument comprises a plate 4 resting on posts 5, and on said plate 4 is a tape carrier 6, formed by a channel or passage 6' of a width corresponding with the width of the tape 7, which is indented or embossed with characters 8 well known in the Morse or other code systems. In the bottom 9 of the channel 6 is a groove 10 over which the tape travels, propelled in the usual manner by being unwound from one spool or reel 45 and wound upon another.

11, 11 indicate posts, each provided with a transverse and adjustable pin 12, 12, on 50 which a shaft 13 is supported, and secured to said shaft is a bar or lever 14, on which a vertically adjustable stylus 15 is supported. To the opposite end of the lever 14 a lever 16, is pivotally secured parallel there- 55 with by a pin 17 and in the rear end of said

lever 16, is an elongated slot 18 engaged by a stud 19, supported in a post 20.

The lever 16 is extensible, the part 21 being telescopically connected therewith as shown, and on the free end of said lever is 60 a resilient member 22, preferably formed of a piece of light spring steel, and on the bottom of said lever is a contact 23. The member 22 may be secured in a slot 24 in the end of the lever 16, by a pin 25, so that it can 65 be moved laterally at its free end.

26 indicates a post on which is a bracket or lateral extension 27 provided with a contact 28, which is engaged by the contact 23 on the lever 16, and in the upper end of said 70 post is a vertically adjustable stud 29 supporting a contact 30 which is engaged by the member 22.

31 is a post in whose upper end is a vertically adjustable screw 32 on which is a 75 member 33 of hard rubber or other suitable non-conductor of electricity which regulates the upward movement of the outer end of the member 22.

The resiliency of the member 22 causes it 80 to augment the impact of the contacts 23 and 28 and 22 and 30 and makes the instrument exceedingly quick in its action in opening and closing an electric circuit in series with a sounder or other electrical instrument. 85

34 is a post supporting a horizontal finger or rod 35 to guide and turn the tape 7 down, as it travels toward the stylus.

The posts 26, 31 and 34, are supported on 90 a plate 36 insulated from plate 4 at 4' and are longitudinally adjustable therein to accommodate extensibility of the lever 16, by means of a screw 37 which is supported in a lug 38 and engages the body or member 39 95 to which said posts are directly secured in any approved manner. The member 39 is provided with an extension 40 which enters and travels in a groove 41 in the plate 36. The tape 7 is guided at the opposite end of 100 the instrument by an arm 42 on the post 20. The elongated slot 18 in the lever 16, enables the lever with its extensible arm 21 to be raised readily for inserting the tape in the channel 6'.

As constructed the levers 14 and 16, form a compound or duplex lever of great sensitivity and effectiveness in the operation of the instrument.

It will be observed that contact at the end 110

of the lever may be made only on 30, or on 23, 28, by properly adjusting the former contact, or the contacts of the two may be combined by the adjustment of the screw stud 5 29 to accommodate conditions of tape. This adjustment makes the electrical contact solid and allows for variations in the thickness of paper or the depth of the indentations. After the contacts are adjusted as required, 10 the adjustment of stylus 15 raises or lowers the levers and makes the electrical contacts lighter or heavier as desired.

The instrument is properly wired for service, the connections being underneath 15 the base-plate 1, and are not shown on the drawings.

The electric circuit is a simple make and break, controlled by the stylus 15 which is vertically adjustable and engages the indentations or embossed dots and dashes on 20 the tape 7 and closes the circuit through the frame 4, levers 14, 16, 23 and 28, and spring 22 and post 30. Post 26 with its bracket 28 and adjustable screw 29, insulated from plate 4 is the other terminal of circuit.

The instrument as constructed is designed for reproducing messages from an embossed tape on local or long distance wires or circuits which can be sent at great speed and 30 reproduced on embossed or printed tape at the distant end of the wire or circuit, or it may be used to send signals in connection with an electric printing typewriter.

The variation of speed of well known 35 means makes the instrument adaptable for working a telegraph sounder or by the use of a pole changing device can be made to repeat for long distance work; or by a suitable code can be worked in direct connection 40 with an electrical typewriter and printing the message.

The advantages of the extensibility of the arm or lever 16, and the adjustability of the contacts engaged thereby, are that the lever 45 by its extensibility can be rendered exceedingly sensitive in its action in transmitting the contact by the stylus in faint indentations in the tape traveling under it, which renders the use of tape of varying quality 50 practical. It is found in practical use that a great variety of paper is supplied, and that in some grades, the indentations are so faint that an ordinary transmitter will not transmit correctly, but skips or jumps over the 55 paper without engaging with the indentations.

Having thus fully described my invention, what I claim is:—

1. An instrument of the class described, 60 comprising a lever provided with an adjustable stylus, a second lever, a resilient member on the end of said second lever, a contact on the lower side of the second lever,

a member having a contact engaged by the contact on said second lever, and a contact 65 engaged by the free end of said resilient member.

2. An instrument of the class described, comprising a lever provided with an adjustable stylus, a second lever, a resilient 70 member on the end of said second lever, a contact on the lower side of the second lever, a member having a contact engaged by the contact on said second lever, and a contact engaged by the free end of said resilient 75 member, and means for regulating the degree of separation of the latter contacts.

3. An instrument of the class described, comprising an extensible lever, a stylus carried by one section of said lever, an embossed 80 tape engaged by said stylus, a resilient member carried on one end and a contact on the lower side of said lever, a contact adjacent the aforesaid contact, and an adjustable member supporting a contact 85 engaged by the free end of said resilient member.

4. An instrument of the class described, comprising a duplex lever, one of which members is pivotally supported at one end 90 and the opposite end pivotally connected to the other member, the latter member being pivotally supported at one end, and means at the opposite end of said member for making and breaking circuit, and a stylus on one 95 of said members.

5. An instrument of the class described comprising a lever provided with an elongated slot at one end and pivotally supported therein, means at the opposite end for 100 making and breaking circuit, and an adjustable stylus connected to said lever and adapted to engage an embossed tape.

6. An instrument of the class described, comprising a base plate, a duplex lever, one 105 member of which lever being pivotally supported at one end and the opposite end pivotally connected to the other member of the lever, the latter member being pivotally supported at one end, a resilient member carried at one end of the last-mentioned member of said lever and a contact on the lower side thereof, a contact supported from the base and arranged adjacent said contact on 110 said lever-member, a stylus carried by the first member of said lever, an embossed tape engaged by the stylus, and a tape guide supported from said base and arranged below said lever to direct said tape in the path of the stylus.

In testimony whereof I affix my signature, in presence of two witnesses:

WILLIAM E. PEIRCE.
